CLAIM

The ornamental design for a combined container/bottle

and cosmetic wand applicators or the like, as shown and described.

DESCRIPTION

FIG. 1 is an exploded front elevational view of a combined container/bottle and cosmetic wand applicators or the like, showing our new design;

FIG. 2 is an exploded rear elevational view showing a second embodiment of our new design wherein the applicators have been modified;

FIG. 3 is a partially exploded side elevational view showing a third embodiment of our new design wherein one applicator has been modified;

FIG. 4 is an opposite side elevational view showing a fourth embodiment of our new design wherein the caps have been modified;

FIG. 5 is a top plan view of FIG. 1;

FIG. 6 is a bottom plan view thereof;

FIG. 7 is an exploded front elevational view of a combined container/bottle and cosmetic wand applicators or the like, showing a fifth embodiment of our new design;

FIG. 8 is an exploded rear elevational view thereof showing a sixth embodiment of our new design wherein the applicators have been modified;

FIG. 9 is a partially exploded side elevational view of FIG. 7 showing a seventh embodiment of our new design wherein one applicator has been modified;

FIG. 10 is an opposite side elevational view showing an eighth embodiment of our new design wherein the caps have been modified;

FIG. 11 is a top plan view of FIG. 7;

FIG. 12 is a bottom plan view thereof;

FIG. 13 is a front elevational view of FIG. 1 with applicator caps on;

FIG. 14 is a side elevational view thereof;

FIG. 15 is a front elevational view of FIG. 7 with applicator caps on; and

FIG. 16 is a side elevational view thereof.
